UNITED STATES PATENT OFFICE.

JOSEPH H. WITTMANN, OF NEW YORK, N. Y.

ENVELOP.

1,164,606.

Specification of Letters Patent. Patented Dec. 14, 1915.

Application filed April 24, 1914. Serial No. 834,127.

To all whom it may concern:

Be it known that I, JOSEPH H. WITTMANN, a citizen of the United States, residing at New York city, in the county of 5 New York and State of New York, have invented certain new and useful Improvements in Envelops; and I do declare the following to be a full, clear, and exact description of the invention, such as will enable others skilled in the art to which it 10 appertains to make and use the same, reference being had to the accompanying drawings, and to the letters and figures of reference marked thereon, which form a part of 15 this specification.

My invention relates to envelops, and more particularly to what is commonly known as a return or "round trip" envelop, which is particularly adapted for use in 20 sending out mail matter calling for a return, and wherein the return to the sender may be made in the identical envelop within which the original matter was delivered.

I am aware of the fact that there are 25 envelops now in use wherein a sealing flap projects from each side of the mouth of the envelop, so that after one of the flaps has been cut and the original contents of the envelop removed, other matter may be 30 placed in the envelop, the second flap used to reseal the same, and the envelop returned to the original sender, whose name may be printed on the second flap;—the double flap envelop which I have just described being 35 shown in my prior Patent No. 978,421.

It is the object of the present invention, however, to provide a return or "round trip" envelop wherein the several flaps are located at the same side of the envelop 40 mouth, and which are so arranged as to obviate the probability of both flaps being cut or damaged when the envelop is first opened. In accomplishing this object I have provided improved details of structure, the preferred forms of which are illustrated in the accompanying drawings, 45 wherein:—

Figure I is a perspective view of an envelop constructed according to my invention, showing the arrangement of the flaps when the envelop is first addressed. Fig. II is a sectional perspective of the same, showing the nesting of the return flap and the combination of the initial sealing and 50 return flaps. Fig. III is a perspective view of the envelop after it has been opened by 55 the first recipient, and showing the short flap attached to the envelop but severed from the return flap. Fig. IV is a perspective view of the envelop as it appears when 60 sealed by the return flap. Fig. V is a sectional perspective of the envelop, showing the parts in position indicated by Fig. IV. Referring more in detail to the parts:—

1 designates an envelop comprising a body 65 portion 2 of any suitable construction, and having one longitudinal edge 3 open to receive a letter or other matter to be sent through the mail. The back ply 4 of the envelop is extended beyond the open edge 70 thereof to form a flap 5, comprising a body or primary flap portion 6, of slightly less width than the body of the envelop, and an extension or secondary flap of substantially less width than the body portion 6, so that 75 when the extension is folded over the front ply of the envelop to seal the initially open edge (as will presently be described) it will not interfere with or obscure an address on the said front ply. The inner face of the 80 extension or secondary flap 7 has a gummed section 8 along its free edge, whereby it may be sealed to the face of the envelop, and the body portion 6 has a gummed section 9 along the edge of the extension, so that 85 when the said body portion is removed from the envelop it may be applied to the front ply of the envelop and sealed thereto when the gum has been moistened.

When the envelop is made ready for use, 90 the body flap 6 is folded along its longitudinal center, so that it may nest in the mouth of the envelop and allow the extension 7 to project therefrom. With this arrangement, the envelop may be addressed, 95 the mail matter inserted, the gum on the short flap moistened, and the short or secondary flap sealed against the front ply of the envelop to seal the latter. When the envelop reaches the person to whom it is 100 addressed, the latter unseals the envelop by slitting the flap along the free edge of the envelop, thereby severing the extension from the body portion of the flap. The contents of the envelop may then be removed and if there is a return to be made to the original sender, the body flap may be drawn out of the envelop, the return matter inserted, and the body flap folded over the front ply of the envelop to cover the name 110 of the original addressee and seal the envelop for its return trip. It is apparent that

with this construction, when the addressee cuts the flap to open the envelop, the body flap bearing the address for the return, is uninjured, and also that when the addressee 5 removes the mail matter from the envelop his attention is called to the contained body flap bearing the address of the original sender, so that when answering the letter he will not overlook the fact that the same 10 envelop in which the letter was received may be used for his reply.

Having thus described my invention, what I claim as new therein, and desire to secure by Letters-Patent, is:—

15 1. An envelop comprising back and address plies, a flap projecting from the back ply at the open edge of the envelop and comprising separate gummed portions forming initial and return flap members, with the 20 return flap member initially nested within the envelop.

2. An envelop comprising front and rear plies, and a flap projecting from one of said plies at the open edge of the envelop; the 25 said flap comprising separate gummed portions forming initial and return flap members adapted for separate sealing to the opposite flap, and having separate opening folds at the edge of the envelop.

30 3. An envelop comprising front and rear plies, and a flap projecting from one of said plies at the open edge of the envelop; the said flap comprising separate gummed portions forming initial and return flap members 35 adapted for separate sealing to the opposite ply, one of the flap members being initially nested within the envelop and folded at the edge thereof to permit the other flap member to seal the envelop without exposing the first flap member.

4. An envelop having an opening at one edge, a flap on one ply of the envelop comprising a wide inner portion and relatively narrow outer portion, with the inner portion 45 originally nested within the envelop and both sections being provided with gummed edges whereby the envelop may be initially sealed by the outer portion and expose an address on the face of the envelop, and whereby the inner flap portion 50 may be withdrawn from the envelop and sealed over the original address.

5. An envelop having an opening at one edge, a flap on the rear ply of the envelop

comprising an inner portion originally 65 nested within the envelop and having an integral outer portion of less width than said inner portion, both the inner and outer portions of the flaps having gummed edges and both being adapted for sealing to the address face of the envelop, whereby the addressed portion is exposed when the sealing is originally effected and concealed by the wider flap portion when the latter is utilized as the sealing member. 60 65

6. An envelop comprising front and back plies and a double sealing flap comprising integral body and extension members, each having a gummed section at its outer edge, with the body portion folded longitudinally 70 to lie within the envelop with its gummed edge along the open edge of the envelop, and with the extension flap projected from the envelop to initially seal the same; the body flap being of sufficient width to cover 75 an addressed portion of the front flap when in sealing position, and the extension flap of substantially less width to expose the addressed portion when in sealing position.

7. An envelop comprising back and address plies, a flap projecting from the back ply at the open edge of the envelop and comprising a return flap member of sufficient width to cover an address on the address ply 80 when in sealing position, and an initial flap 85 portion at the free edge of the return member, of less width than the return member and arranged when in sealing position to expose an address on the address ply.

8. An envelop comprising back and address plies, a flap extending from the back ply at the open edge of the envelop and comprising a base return member and an initial sealing member at the free edge of the return member; the return member being initially nested within the envelop and of greater width than the initial sealing member, whereby an address is exposed when the envelop is sealed by the initial member and the severed initial member and the address 95 covered by the return member when the latter is in sealing position. 100

In testimony whereof I affix my signature in presence of two witnesses.

JOSEPH H. WITTMANN.
